DESIGN FOR A WOVEN FABRIC

Charles W. Clackett, New York, N. Y.

Application November 8, 1934, Serial No. 53,940

Term of patent 3½ years

To all whom it may concern:

Be it known that I, Charles W. Clackett, a citizen of the United States, residing at 107-11 86th Avenue, Richmond Hill, in the county of Queens and State of New York, have invented a new, original, and ornamental Design for a Woven Fabric, of which the following is a specification, reference being had to the accompanying drawing, forming a part thereof.

The figure is a view of a piece of fabric showing my new design.

I claim:

The ornamental design for a woven fabric substantially as shown.

CHARLES W. CLACKETT.
